2,668,740

PACKING RETAINER FOR JOURNAL BOXES

John D. Herr, Minerva, Ohio, assignor of one-fourth to Dick W. Mount, Minerva, Ohio

Application March 2, 1953, Serial No. 339,527

8 Claims. (Cl. 308—89)

1

The invention relates to retainers for the packing in journal boxes, and more particularly to a simple and efficient device for retaining waste in proper position in the journal box of a railway car.

One object of the invention is to provide a packing retainer which is so constructed that it will permit of easily placing waste or similar packing in the journal box, and which will retain the packing in proper position during relative movement between the journal and the box.

Another object is to provide such a packing retainer having an adjustment therein which compensates for relative longitudinal movement between the journal and the box.

A further object is to provide a packing retainer formed of flat, non-abrasive sheet material such as copper, bronze, brass, plastic material or the like, comprising an arcuate rear member to the upper ends of which are adjustably connected substantially horizontal members, an arcuate front member being connected to the forward ends of said horizontal members.

A still further object is to provide a packing retainer of this character in which the front arcuate member is formed of two hinged parts with spring means associated therewith for urging the same toward the journal.

Another object is to provide a packing retainer of the type referred to in which the front arcuate member is hingedly connected to the forward ends of the horizontal members and adapted to be swung upwardly therefrom to permit packing to be placed in the box beneath the journal.

It is also an object of the invention to provide such a packing retainer in which adjustable spring means connects the horizontal members to the rear arcuate member.

The above objects together with others which will be apparent from the drawing and following description, or which may be later referred to, may be attained by constructing the improved packing retainer in the manner hereinafter described in detail and illustrated in the accompanying drawing, in which:

Fig. 1 is a detached, perspective view of a packing retainer embodying the invention;

Fig. 2 a vertical, longitudinal sectional view through a journal box, showing the improved packing retainer located therein;

Fig. 3 a transverse, vertical, sectional view through the journal box, taken as on the line 3—3, Fig. 2;

Fig. 4 a horizontal, longitudinal, sectional view, taken as on the line 4—4, Figs. 2 and 3; and

2

Fig. 5 a fragmentary perspective view of a modified form of adjustment.

Referring now to the embodiment of the invention illustrated, in which similar numerals refer to similar parts throughout, a conventional type of journal box for railway cars is indicated generally at 10, containing the journal 11, and adapted to be closed by the usual cover 12.

The bearing 13, located in the top of the journal box, is supported by the journal 11, and the bearing is engaged by the wedge 14 which engages the top of the journal box, all as in usual and well-known practice in the construction of such journal boxes.

15 The journal extends into the journal box through an opening 15 on the inner side of the journal box, said aperture being provided with any conventional oil seal 16, having a circular opening 17 for engaging the enlarged, cylindrical portion 18 of the journal.

19 Suitable packing, preferably the customary waste, as indicated at 19, is located in the bottom of the journal box and extends up into engagement with the bottom of the journal and with the sides of the journal to a predetermined point, as is customary in the packing of journal boxes.

20 The packing 19 preferably terminates adjacent to the outer end of the journal, leaving an open space 20 to serve as a well for excess lubricant, the level of which is indicated at 21. This lubricant is soaked up by the waste, and by capillary attraction it is drawn up into the upper portion of the waste and thus deposited upon the rotating journal 11, keeping the journal lubricated at all times.

25 Referring first to the embodiment of the invention illustrated in Figs. 1 to 4 inclusive, the packing retainer to which the invention pertains 30 may be formed of any suitable non-abrasive sheet metal, such as copper, bronze, brass or the like, or of plastic or other suitable non-abrasive material.

35 As best shown in Fig. 1, in which the improved packing retainer is shown removed from the journal box, the device includes the arcuate rear member 22 having the substantially semi-circular upper or inner edge 23 shaped to conform to the curvature of the journal at the rear end of the box, as will be later described.

40 The upper ends of the member 22 terminate in forwardly disposed, substantially horizontal arms 24, each having a suitable projection at its forward end, such as a stud 25, to provide a stop. 45 If desired, each arm 24 may be reinforced, so

as to hold it rigidly perpendicular to the rear member 22, as by the angle member 26 attached by any usual and well-known means, such as by welding.

A forwardly projecting lug 27 may be formed at the lower edge of the rear arcuate member 22, for contact with the bottom of the journal box and, if desired, a curved spring 27a may be attached to the lug 27 and extend forwardly therefrom, for the purpose of urging packing upward into contact with the journal. The lug 27, contacting the bottom of the journal box, will tend to prevent the retainer from rotating around the journal in the direction of its travel.

The horizontal members 28 are longitudinally, adjustably connected to the arms 24, as by the loops 29 fixed upon the members 28 as by rivets 30 of the like, and slidably mounted upon the arms 24, the studs 25 upon said arms limiting forward sliding movement of the loops 29 upon the arms 24.

A front arcuate member, indicated generally at 31, is hingedly attached to the forward ends of the horizontal members 28, as indicated at 32, so that it may be swung upward from the full line position to the dotted line position shown in Fig. 1, to facilitate the placing of packing in the journal box as will be later described.

The front member 31 is preferably formed of two similar parts, indicated at 33 and 34, which are pivotally connected together as at 35, and provided with suitable resilient means, such as the spring 36 connected at opposite ends to the studs 37, for normally urging the members 33 and 34 toward each other for a purpose to be later explained.

In order to place packing in the journal box, the packing retainer shown in Fig. 1 is first inserted into the journal box through the opening 38, the cover 12 being of course held open. The rear arcuate member 22 of the packing retainer is located toward the rear of the journal box, the front arcuate member 31 being swung upward upon its hinges 32 to the dotted line position shown in Fig. 1, and being located forwardly of the collar 39 on the front or outer end of the journal.

This permits the waste or packing material to be placed in the lower portion of the journal box beneath the horizontal member 28 of the packing retainer and around the underside of the journal 41.

When the proper amount of packing has been placed in the journal box, in the manner above described, the front arcuate member 31 is swung downward upon its hinges 32 and is slightly expanded by pulling the parts 33 and 34 thereof outwardly so that they pivot upon the pivot point 35.

With the front arcuate member in this position it may be moved backward under the collar 39 of the journal, moving the entire packing retainer and the packing to the position best shown in Figs. 2 and 4 of the drawing.

When the pull upon the parts 33 and 34 of the front arcuate member is released, the spring 36 will move these parts toward each other into substantial engagement with the underside of the journal 41 just to the rear of the collar 39 thereof.

The rear arcuate member 22 of the packing retainer will surround the enlarged portion 18 of the journal and will rest against the back wall of the journal box, the forwardly disposed lug 27 thereof resting upon the bottom wall of the journal box, as best shown in Fig. 2.

The working parts of the packing retainer are thus free to move in conjunction with the journal and journal box in their lateral, horizontal and vertical movements and will at all times hold the packing in proper place.

It will be seen that any relative longitudinal movement between the journal and the journal box will be compensated for by the longitudinal adjustment of the horizontal members 28 of the packing retainer relative to the rear arcuate member 22 thereof.

The packing retainer is thus not anchored in any part of the journal box but is free to move in all directions with the journal, while at the same time preventing the packing from moving up around the top of the journal and lodging under the bearing.

It will also be seen that the improved packing retainer will prevent lateral movement of the packing relative to the journal, thus preventing it from working out from under the journal. The horizontal members 28 will at all times prevent vertical displacement of the packing while the front and rear arcuate members 22 and 31 will prevent horizontal displacement of the packing.

In Fig. 5 is shown a modified form of adjustment between the rear arcuate member 22' and the horizontal member 28'. As shown, the rear ends of the horizontal members 28' are connected to the upper ends of the rear arcuate member by means of inverted, U-shape springs 40.

These springs should be positioned so that they will tend to normally urge the horizontal members 28' forward, relative to the rear arcuate member 22', so as to normally position the front arcuate member 31 against the inner side of the collar 39 of the journal.

Relative longitudinal movement between the journal and journal box will thus be compensated for. If desired, in order to maintain the journal members 28' substantially horizontal, pins 41 may be fixed to the upper ends of the rear arcuate member 22' and extend through openings 42 in the springs 40, permitting the forward portion of each spring to move upon these pins as the packing retainer automatically adjusts itself to compensate for relative movement between the journal and journal box.

Except for the spring adjustment shown in Fig. 5, this form of packing retainer may be otherwise constructed as best shown in Fig. 1, that is, a front arcuate member such as shown at 31 in Fig. 1 may be hinged to the forward ends of the horizontal members 28', and the operation of this form of the invention will be as above described.

With the construction illustrated and above described, the packing retainer is first placed in the journal box, after which the packing is inserted. The placing of the retainer in position thus does not disturb the packing, as is the case with the forms of packing retainers now in general use.

The retainer cannot be removed without first removing the packing. This prevents packing retainers from being readily stolen or discarded, by neglect on foreign roads. The construction also facilitates normal practice of inspection and service while cars are in the yards or en route.

In the foregoing description, certain terms have been used for brevity, clearness and understanding, but no unnecessary limitations are to be implied therefrom beyond the requirements of the prior art, because such words are used for de-

scriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. A packing retainer for journal boxes, comprising an arcuate rear member, forwardly disposed, parallel, substantially horizontal members, spring means adjustably connecting the horizontal members to the upper ends of the arcuate rear member, an arcuate front member and means hingedly connecting the arcuate front member to the forward ends of the horizontal members, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

2. A packing retainer for journal boxes, comprising an arcuate rear member, forwardly disposed, parallel, substantially horizontal members connected to the upper ends of the arcuate rear member, an arcuate front member and means hingedly connecting the arcuate front member to the forward ends of the horizontal members, the arcuate front member comprising two similar parts, means pivotally connecting said parts together and spring means for urging said parts toward each other, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

3. A packing retainer for journal boxes, comprising an arcuate rear member, forwardly disposed, parallel, substantially horizontal members, means adjustably connecting the horizontal members to the upper ends of the arcuate rear member, an arcuate front member and means hingedly connecting the arcuate front member to the forward ends of the horizontal members, the arcuate front member comprising two similar parts, means pivotally connecting said parts together and spring means for urging said parts toward each other, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

4. A packing retainer for journal boxes, comprising an arcuate rear member, forwardly disposed, parallel, substantially horizontal members, spring means adjustably connecting the

horizontal members to the upper ends of the arcuate rear member, an arcuate front member and means hingedly connecting the arcuate front member to the forward ends of the horizontal members, the arcuate front member comprising two similar parts, means pivotally connecting said parts together and spring means for urging said parts toward each other, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

5. A packing retainer for journal boxes, comprising an arcuate rear member, forwardly disposed arms at the upper ends of the arcuate rear member, parallel horizontal members, means slidably adjustably connecting the horizontal members to said arms, an arcuate front member and means hingedly connecting the arcuate front member to the forward ends of the horizontal members, the arcuate front member comprising two similar parts, means pivotally connecting said parts together and spring means for urging said parts toward each other, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

6. A packing retainer for journal boxes, comprising an arcuate rear member, inverted U-shape springs connected to the upper ends of the arcuate rear member, forwardly disposed, parallel, substantially horizontal members connected to the inverted U-shape springs, an arcuate front member and means hingedly connecting the arcuate front member to the forward ends of the horizontal members, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

7. A packing retainer for journal boxes, comprising an arcuate rear member, inverted U-shape springs connected to the upper ends of the arcuate rear member, forwardly disposed, parallel, substantially horizontal members connected to the inverted U-shape springs, horizontal pins fixed to the upper ends of the arcuate rear member, there being apertures in the U-shape springs through which said pins are located, an arcuate front member and means hingedly connecting the arcuate front member to the forward ends of the horizontal members, said packing retainer adapted to be arranged within the journal box with the rear and front arcuate members near opposite ends of the journal for holding packing introduced into the journal box against horizontal displacement, and the horizontal members adapted to be arranged on opposite sides of the journal for preventing vertical displacement of the packing.

8. A packing retainer for journal boxes, comprising an arcuate rear member, inverted U-

shape springs connected to the upper ends of the arcuate rear member, forwardly disposed, parallel, substantially horizontal members connected to the inverted U-shape springs, an arcuate front member and means hingedly connecting the arcuate front member to the forward ends of the horizontal members, the arcuate front member comprising two similar parts, means pivotally connecting said parts together and spring means for urging said parts toward each other, said packing retainer adapted to be arranged within the journal box with the rear and front arcuate members near opposite ends of the journal for holding packing introduced into the journal box

against horizontal displacement, and the horizontal members adapted to be arranged on opposite sides of the journal for preventing vertical displacement of the packing.
